(57) **CLAIM**

The ornamental design for an umbrella handle, as shown and described.

DESCRIPTION

FIG. 1 is a left-rear perspective view of my umbrella handle according to my new design;

FIG. 2 is a right-rear perspective view thereof;

FIG. 3 is a left-bottom perspective view thereof;

FIG. 4 is a left side view thereof;

FIG. 5 is a rear view thereof;

FIG. 6 is a right side view thereof;

FIG. 7 is top plan thereof; and,

FIG. 8 is bottom plan view thereof.

The broken lines depict portions of the umbrella handle that form no part of the claimed design. The broken lines act as boundaries to the claimed design.
